PROCESS AND APPARATUS FOR CLEANING
STEAM FROM A STEAM BOILERDavid S. Jacobus, Montclair, N. J., assignor to The
Babcock & Wilcox Company, Bayonne, N. J., a
corporation of New JerseyApplication January 19, 1928, Serial No. 247,765
Renewed November 11, 1932

10 Claims. (Cl. 122—459)

This invention relates to a process and apparatus for removing impurities from steam by washing the steam with water and then separating the wash water and impurities from the steam. The invention is especially useful for removing moisture and solid impurities from steam after it leaves the steam space of the boiler and before it reaches the superheater that may be provided for superheating the steam.

10 The invention will be understood from the description in connection with the accompanying drawings in which Fig. 1 is a side view partly in section showing an illustrative embodiment of the apparatus for practicing the invention; Fig. 2 is a vertical section on an enlarged scale, through the valve controlling device; Fig. 3 is a view similar to Fig. 1 showing a modification; and Fig. 4 is a vertical section through a modification of one of the parts.

20 In the drawings, reference character 1 indicates a water tube boiler that is provided with a superheater 2 and a steam and water drum 3. A pipe 4 leads from the steam space of the steam and water drum 3 to a larger pipe 5 that is 25 preferably vertical, in which a twisted metal band 6 may be located, similar to the one shown in Fig. 15 of U. S. Patent #1,149,265. The lower end of the pipe 5 is connected to a steam and water separator 8 that may be of one of the 30 well known types. A steam pipe 9 leads from the steam and water separator 8 to the superheater 2, and an outlet pipe 10 for the water leads from the lower end of the steam and water separator 8 to a heat interchanger 11.

35 An outlet pipe 12 is provided near the lower portion of the heat interchanger 11 and is controlled by the valve 13 which is in turn controlled by the float 14 in the heat interchanger 11. A hand controlled blowoff valve 15 is provided at the bottom of the heat interchanger 11. An inlet 16 for clear distilled water leads to the coil 17 inside the heat interchanger, and an outlet pipe 18 leads from this coil to the pipe 5 above the upper end of the ribbon 6, a 45 valve 19 being provided in the pipe 18.

A valve 25 that is automatically controlled by the rate of flow of steam from the boiler is also located in the pipe 18.

The extent of opening of the valve 25 is made 50 to depend upon the rate of flow of steam from the boiler so that the amount of wash water for the steam will be proportional to the amount of the steam generated. This control can be effected by connections to different portions of the system through which the steam flows, and between

which portions there will be a differential in pressure in accordance with the rate of flow of steam. In the illustrated embodiment of the invention, the valve 25 is controlled by having an orifice 26 in the pipe 4 with connections 27 and 28 on opposite sides of the orifice 26 to the valve control mechanism or device in the casing 29. The pipes 27 and 28 may be connected to any two parts of the boiler, superheater or piping where there will be a material fall of pressure on increasing the rate of flow of steam from the boiler and no orifice employed, such as the one shown at 26. A number of metal diaphragms 30 connected to form a bellows, is located inside the casing 29 and is made to contract and expand in accordance with the differential of pressure in the pipes 27 and 28. The pipe 27 leads steam into the casing 29 on the outside of the bellows and the pipe 28 leads steam into the inside of the bellows. The bellows is connected by the link 32 to a lever 33 that is attached to the shaft 34 which extends through a stuffing box to the outside of the casing. One end of the lever 35 is attached to the outwardly extending part of the shaft 34 and the other end of this lever is connected by means of a link 36, to a lever 37 that is attached to the shaft 38. A lever 39 carrying a slideable or adjustable weight 40 is also connected to the shaft 38 and the shaft 38 extends into a housing 41. One end of the lever 42 inside the housing 41 is attached to the shaft 38 and the other end of this lever is connected to the stem 43 of the valve 25.

The operation is as follows: Steam passes 90 through the pipe 4 into the vertical pipe 5 where clean distilled water, which is of greater purity than that contained in the boiler, is mixed with the steam and washes out the moisture and other impurities, the washing of the steam being facilitated by the twisted strip 6. The mixture of 95 steam and water is separated in the separator 8, the steam going through a pipe 9 to the superheater, and the water and impurities passing into the heat interchanger 11. The float 14 controls the valve 13 so that the water escapes from the 100 heat interchanger 11 at approximately the same rate as it enters and at the same time a sufficient amount of water is kept in the heat interchanger to cover the coil 17. Water other than distilled water may be employed for washing the steam 105 provided it does not contain too great a proportion of solids, depending upon the degree of purity desired in the steam and the effectiveness with which the steam is freed from the wash water.

The solids that settle in the bottom of the heat interchanger 11 can be blown off from time to time from the blowoff pipe 15. Clean distilled water enters the inlet 16 and the coil 17 and is heated, thereby saving heat that would otherwise be wasted. The water passes through the pipe 18 into the vertical pipe 5 at a rate proportional to the amount of steam leaving the boiler and controlled by the rate of steam flow.

10 An increase in the rate of wash water for the steam is caused to take place by an increase in the rate of steam flow, because an increased differential in pressure between the steam in the pipes 27 and 28 takes place when the rate of 15 steam passing through the orifice increases, so that the bellows 30 is collapsed, and by means of the lever mechanism and shafts, the valve 25 is opened more. By adjusting the levers 39 and 42 on the shaft 38 and also adjusting the weight 40 20 on the lever 39, the proportions of wash water to the steam can be varied. In accomplishing this adjustment the lever 39 may be turned to any required angle on the shaft 38, for example, it might be placed in the dotted line position shown 25 in Fig. 2.

In the modification shown in Fig. 3, the pipe 4 from the steam space of the steam and water drum 3 divides into two valved branches 50 that lead to vertical chambers 51 and 52. The chambers 51 and 52 are provided with metallic grids through which and over which steam passes with water that is sprayed into the same for washing the steam. Outlet pipes 54 and 55 from the lower ends of the chambers 51 and 52 lead to steam and 30 water separators 56 and 57, respectively. The hand valve control blowoff pipes 58 and 59 lead from the lower ends of the separators 56 and 57, and pipes 62 controlled by valves 63 and 64 lead from the steam spaces of the separators 56 and 35 40 57 to a pipe 65 that leads to a steam and water separator 66. A blowoff pipe 67 is connected to the lower end of the separator 66 and a steam trap 68 is located in this blowoff. A steam pipe 69 leads from the steam space of the separator 45 56 to the superheater 2. Valved pipes 70 and 71 lead from the normal water level in the separators 56 and 57 to the heat exchanger 72 that is provided with a float 73 to control the valve 74 in the 50 discharge pipe near the lower end of the heat exchanger 72. A blowoff pipe 75 with a hand controlled valve is provided at the bottom of the 55 exchanger 72.

The control mechanism 29 like the one already described in connection with Fig. 1, controls the valve 76 in the water inlet pipe 77 in accordance with the rate of steam passing through pipe 4. The pipe 77 leads to coil 78 in heat exchanger 72, from which coil a pipe 79 with valved branches leads to sprayers 80 and 81 in 60 chambers 51 and 52. Valved pipe connections 82 and 83 are provided for supplying a large flow of water for washing the grids should they become coated with solid matter from the steam.

The operation of the device shown in Fig. 3 is 65 similar to that already described in connection with Fig. 1. In this device either spraying cylinder and separator may be shut off by closing the appropriate valves for cleaning or repair without interfering with the operation of the other cylinder and separator. In washing the grids by means of valved pipe connections 82 or 83, the spraying cylinder that is being washed may be shut off from the other by means of valves provided 70 in the pipe connections.

75 The spraying chamber 85 shown in Fig. 4, is

provided with staggered sloping overlapping trough-shaped baffles 86 extending inwardly from opposite sides of the inside walls of the chamber, so arranged that when water is sprayed through the steam it collects at the bottom of the trough-shaped arrangements and is blown along with the steam from one of the trough-shaped arrangements to the next one below and made to mingle with the steam as the steam flows downwardly through the vertical cylinder.

I claim:

1. In a boiler having a steam drum and a superheater, means for spraying wash water into the steam as it passes from said drum to said superheater, and separating the water from the steam before it passes into said superheater, a heat exchanger utilizing said separated water for heating wash water, and a float for regulating the depth of water in said heat exchanger.

2. In a steam boiler, a superheater, means for conducting saturated steam from the steam space of said steam boiler, means for washing said saturated steam with water of greater purity than that in said boiler, means for regulating the amount of wash water in proportion to the flow of steam from said boiler, means for separating the excess water from said steam, means for removing the excess water so separated from the steam, and means for delivering the cleaned steam to said superheater.

3. In a steam boiler, a superheater, means for conducting saturated steam from the steam space of said steam boiler, means for washing said saturated steam with water of greater purity than that in said boiler, means for separating the excess water from said steam, means for removing the excess water so separated from the steam, means for delivering the cleaned steam to said superheater, and means for heating said wash water by the excess water removed from the steam.

4. In a boiler having a steam drum and a superheater, means for spraying wash water into the steam as it passes from said drum to said superheater, and separating the water from the steam before it passes into said superheater, and a heat exchanger utilizing said separated water for heating the wash water.

5. In a boiler having a steam drum and a superheater, means for spraying wash water into the steam as it passes from said drum to said superheater, and separating the water from the steam before it passes into said superheater, a heat exchanger utilizing said separated water for heating the wash water, and means for regulating the depth of water in said heat exchanger.

6. In combination with a steam boiler and superheater, means interposed between the two for removal of solids from wet steam and including means contacting water of greater purity than the boiler water with the wet steam in washing relation whereby only purified steam is delivered to the superheater, and means regulating the wash water supplied in accordance with the boiler load.

7. The method of operating a steam boiler and superheater with a steam washing device for removing solids, which comprises contacting water of greater purity than the boiler water with wet steam in washing relation before the steam enters the superheater, and regulating the amount of water so contacted in accordance with the boiler load.

8. The method of reducing the solid concentration of wet steam containing solids in solution

- in the suspended moisture which comprises passing substantially all of the wet steam through a steam space in an intimate and substantially uniform contact with water of less solid concentration than the suspended moisture sufficient to substantially lower the solid concentration of the suspended moisture, and subsequently subjecting the treated steam to a steam and moisture separating action. 5
9. The method of reducing the solid concentration of wet steam containing solids in solution in the suspended moisture which comprises passing the wet steam through a steam space and diluting the water solution of solids forming the moisture suspended in the steam with water of less solid concentration to lower the solid concentration of the moisture, and subsequently subjecting the treated steam to a steam and moisture separating action. 80
10. The method of reducing the solid concentration of wet steam containing solids in solution in the suspended moisture which comprises spraying water of less solid concentration than the suspended moisture into the wet steam to lower the solid concentration of the suspended moisture, and subsequently subjecting the treated steam to a steam and moisture separating action. 85
